(57) CLAIM

The ornamental design of a shoe, as shown and described.

DESCRIPTION

FIG. 1 is a side view of a shoe; and, FIG. 2 is another side view of the shoe of FIG. 1, from the opposite side of the shoe as FIG. 1.

The portions of the shoe surrounded by dashed lines form no part of the claimed design. The dashed lines are boundaries and form no part of the claimed design.

1 Claim, 1 Drawing Sheet
